UNITED STATES PATENT OFFICE.

FREDERICK P. HALL, OF NEWARK, NEW JERSEY, ASSIGNOR TO SIMPLEX RADIO DEVICES, INC., OF NEW YORK, N. Y., A CORPORATION OF NEW JERSEY.

MICROCOUPLER.

Application filed June 16, 1926. Serial No. 116,497.

My invention relates broadly to tuning apparatus for electrical circuits, and more particularly to a construction of variable coupling device for connection in electrical circuits.

One of the objects of my invention is to provide a new and novel construction of a coupling device for electrical circuits whereby accurate and delicate adjustments in coupling inductances connected to various parts of an electrical system may be secured by a micrometer screw action and a lever movement, controlling the movement of an inductance mounted on one or more swinging arms.

Another object of my invention is to provide an arrangement of coupling coils whereby axial adjustment of one inductance may be secured for varying the coupling with respect to another inductance while angular adjustment of one or more inductances may be obtained with respect to the first mentioned axially adjustable inductance.

Still another object of my invention is to provide a method in an electrical coupling system for simultaneously changing the magnetic and electric field angle and the coupling distances between inductances for securing accurate conditions of coupling capable of minute changes in order to meet the required conditions in the electrical circuits.

A still further object of my invention is to provide a construction of tuning apparatus including a pair of primary and secondary coupling inductances each longitudinally and angularly adjustable with respect to each other, and a movable coil having means for effecting increment movement thereof with respect to the primary and secondary inductances.

Other and further objects of my invention will be understood from the specification hereinafter following by reference to the accompanying drawings, in which:

Figure 1 is a side elevation illustrating the arrangement of parts of the tuning apparatus of my invention; Fig. 2 is a plan view showing the relative position of the several windings included in the tuning apparatus; Fig. 3 is an end view of the tuning apparatus illustrated in Figs. 1 and 2; Fig. 4 is a fragmentary view partially in cross section on line 4—4 of Fig. 3 showing one method I may provide for mounting one of the inductances; Fig. 5 is a fragmentary view showing a method of mounting another of the inductances of the tuning apparatus; Fig. 6 is a side elevation of the inductance mounting illustrated in Fig. 5; Fig. 7 is an enlarged view of the micrometer adjustment device which I provide for securing angular displacement of one of the windings in the coupling system; Fig. 8 is a cross-sectional view through the micrometer adjusting device of Fig. 7; Figs. 9, 10, 11 and 12 are views of parts of the micrometer adjustment device; and Figs. 13 and 14 show modified constructions of mountings for the coupling coils of the apparatus.

I have illustrated my invention as applied to a tuning apparatus particularly intended for operation in radio receiving circuits, but I desire it be understood that the apparatus may be employed in various electrical circuits wherever a precise variation in coupling of the inductances is desired and where the control of the coupling is to be obtained from the exterior of a panel behind which the tuning apparatus is mounted. I provide a construction by which very accurate adjustment of coupling may be obtained and by which increment displacement of a third coil may be obtained with respect to the primary and secondary coils which are also capable of an independent coupling adjustment. I have illustrated windings of circular contour employed in the tuning apparatus, but it will be understood that various shapes of coils may be employed and that the micrometer adjustment which I provide may be associated with removable or detachable honeycomb coil inductance devices which may be angularly adjusted with respect to each other.

Referring to the drawings in detail, reference character 1 represents a panel with respect to which the tuning apparatus of my invention is mounted. A bracket member 2 is provided which is secured in contact with the panel by means of the screw threaded members 3 and 4 which provide a bearing for the control shaft 5 which may be operated from the front of the panel by means of knob 6. The control shaft 5 has a cotter pin 9 passing through the end thereof forming with washer member 7 a limit for the movement of the screw threaded carriage member 8 which has a tongue formed thereon and passing through the elongated aperture 15 in the angle piece 14. The angle piece 14 is pivotally mounted with respect to the bracket 2 by means of the side extensions 12 which cooperate with simi-

lar side extensions 10 on bracket 2 with ball bearings 11 interposed therebetween in socket portions 10^a. The angle piece 14 is connected by means of spring 16 with the bracket 2 in such manner that the angle piece 14 is continuously urged outwardly against the carriage member 8. The bracket member 2 is bent at an angle as illustrated and carries an insulated strip member 17 providing a means for supporting a plurality of terminals represented at 18, 19, 20 and 21 for establishing connection with the several windings of the tuning apparatus. The bracket member 2 also provides a support for a pair of longitudinally extending rod members 22 which are positively spaced at their outer ends by means of strip member 23. The rod members 22 serve as supports along which the inductance coil 24 may be longitudinally adjusted in position. The inductance coil 24 may be of the loose basket wound type arranged in such manner as to support an adjacent inductance coil. The adjacent inductance coil which may form the primary coil of the tuning apparatus may be of the self-supporting type as represented at 28 positioned as shown in Fig. 5 in the slotted supports 27 with the terminals thereof connected to binding posts 29 and 30 carried by insulated strip member 25. The coil 28 may be adjustably positioned with respect to coil 24 by means of the longitudinally extending rod members 26 which pass through the basket wound coil 24. The winding 28 may be supported in a variety of ways, as I have illustrated in Figs. 13 and 14 where the coil support 31 may be provided or where an insulated skeleton frame 32 having slotted extremities thereon may serve as the coil supporting means. The windings may also be mounted for angular adjustment and movement. The third winding of the tuning apparatus is represented at 33 carried by the angular extension 34 of the angle member 14. This third winding may be of the spider web construction arranged in such manner that close coupling may be secured with respect to the windings 28 and 24. It will be observed that coil 33 may be moved by increments to various positions such as the dotted line position 33^a under control of the knob 6 and screw threaded shaft 5. By providing a very fine pitch to the screw threads of shaft 5 extremely accurate adjustment of the tuning apparatus may be secured. By this construction a simultaneous change in the magnetic and electric field angle and the coupling distance between the coils may be secured. Individual adjustment in the position of coils 24 and 28 may be readily made and the windings finally located in a position where the associated electrical circuits may be controlled at maximum efficiency. The coil structure 25, 26, 27 and 28 is extremely light and does not place any undue strain upon the basket wound inductance

24 which serves as the sole means of support for the coil system 28. The rod members 26 are shaped of such size that they readily pass through and are longitudinally adjustable within the spaces between the basket 70 woven turns of the inductance 24.

The invention as illustrated herein has been found to be very practical in its construction and arrangement of parts. However, I desire it to be understood that modifications 75 may be made and that no limitations upon the invention are intended other than are imposed by the scope of the appended claims.

What I claim as new and desire to secure by Letters Patent of the United States is as 80 follows:

1. Tuning apparatus comprising in combination a bracket member, a pair of longitudinally extending rod members supported by said bracket member, an inductance coil 85 adjustably positioned on said rod members, means adjustably carried by said inductance coil for supporting a cooperating inductance coil in spacial relation thereto and a separate inductance adjustably carried by said bracket 90 member for movement with respect to said first mentioned inductance coils.

2. Tuning apparatus comprising in combination a bracket arranged to be mounted adjacent a panel structure and extend at an angle therefrom, an insulated frame structure supported by said bracket, an inductance coil adjustably positioned upon said frame structure, an auxiliary insulated frame structure slidably carried by said inductance coil, means carried by said auxiliary frame structure for supporting a cooperating inductance coil in spacial relation to said first mentioned inductance coil, and a third inductance coil adjustably carried by said bracket 100 and means controllable from one side of said panel structure for adjusting the position of said last mentioned inductance coil with respect to said first mentioned inductance coil. 105

3. A tuning apparatus comprising in combination a bracket arranged to be mounted adjacent the rear of a panel structure, an insulated frame structure carried by said bracket, an inductance coil slidably mounted on said frame structure, a supplemental 115 frame structure slidably carried by said inductance coil, an inductance coil supported by said supplemental frame structure and arranged to be coupled with said first mentioned inductance coil, and a third inductance coil adjustably carried by said bracket and arranged to be moved into and out of the field of said aforementioned inductance coils.

4. Tuning apparatus comprising in combination a bracket member arranged to lie 125 immediately adjacent a panel structure, a bearing member passing through said bracket member and said panel structure, a shaft member journaled in said bearing member and rotatable from one side of said panel 130

- structure, a pair of inductance coils supported by said bracket member, an angle member pivotally mounted with respect to said bracket member and controllable in position by rotation of said shaft member, said angle member carrying an inductance coil variable in spacial relation with respect to said aforementioned inductance coils. 5
5. Tuning apparatus comprising in combination a bracket member arranged to be mounted upon the rear of a panel structure, a bearing carried by one end of said bracket member and a coil support carried by the other end of said bracket member, a pair of 10 inductance coils carried by said support, an angle member pivotally mounted intermediate the ends of said bracket member and carrying an inductance coil spacially related to said aforementioned inductance coils, a mi- 15 crometer adjustment screw journaled in said bearing and connections between said micrometer adjustment screw and said angle member for controlling the angular position of the inductance coil carried by said angle member with respect to the inductance coils supported from said bracket member. 20
6. Tuning apparatus comprising in combination a bracket member arranged to be secured adjacent the rear of a panel structure, a bearing carried by one end of said bracket member and a coil support carried by the opposite end thereof, a pair of inductance coils carried by said support, an angle member pivotally mounted in a position intermediate the 25 ends of said bracket member, means for constantly urging said angle member in the direction of said coil support, an inductance coil carried adjacent one end of said angle member, a micrometer screw journaled in said bearing and means controlled by said micrometer screw in engagement with the opposite 30
- end of said angle member for controlling the movement of the inductance coil carried by said angle member with respect to the inductance coils carried by said coil support. 45
7. Tuning apparatus comprising in combination a bracket member arranged to be mounted on the rear of a panel, a plurality of inductance coils supported from said bracket member, an angle member adjustably positioned with respect to said bracket member, an inductance carried by said angle member, and a pair of ball members located between opposite sides of said angle member and said bracket member for facilitating adjustment 50 of said angle member in said bracket member. 55
8. Tuning apparatus comprising in combination a bracket member for supporting an inductance device, an angle member carrying a separate inductance device, and means for journaling said angle member in said bracket member comprising a pair of ball members forming a readily adjustable joint between said bracket and angle members and confining the movement of said angle member to a 60 plane including said bracket member. 65
9. Tuning apparatus comprising in combination a bracket member, an inductance device supported by said bracket member, a pair of side extensions carried by said bracket 70 member, an angle member, an inductance device carried by said angle member, a pair of side extensions on said angle member directed toward the side extensions on said bracket member and a ball member located 75 between each of said side extensions for journaling said angle member with respect to said bracket member and providing a readily adjustable joint therebetween.

In testimony whereof I affix my signature.

FREDERICK P. HALL.
